UNITED STATES PATENT OFFICE.

EDWARD M. HEWLETT, OF SCHENECTADY, NEW YORK, ASSIGNOR TO THE
GENERAL ELECTRIC COMPANY, OF NEW YORK.

DESIGN FOR A THIRD-RAIL INSULATOR.

SPECIFICATION forming part of Design No. 29,741, dated November 29, 1898.

Application filed November 7, 1898. Serial No. 695,751. Term of patent 14 years.

To all whom it may concern:

Be it known that I, EDWARD M. HEWLETT, a citizen of the United States, residing at Schenectady, in the county of Schenectady, State of New York, have invented and produced a certain new and original Design for Third-Rail Insulators for Electric Railways, (Case No. 851,) of which the following is a specification.

The accompanying drawing shows the design in perspective. Its leading feature consists of a hexagonal cup or cap upon which the rail is to rest. Its general features consist of a base A, of tripod shape, having lugs $a a$, provided with bolt-holes $a' a'$, there being three of these lugs forming the feet of the tripod.

The upper part consists of a conical frustum B. Upon this rests the cap C, of hexagonal shape, formed with the lugs $c c$, slightly cut away on their corners and having the circular base C'.

What I claim is—

The design for a third-rail insulator, substantially as shown and described. 25

In witness whereof I have hereunto set my hand this 31st day of October, 1898.

EDWARD M. HEWLETT.

Witnesses:

B. B. HULL,
M. H. EMERSON.
